UNITED STATES PATENT OFFICE.

CHARLES L. JOHNSON, OF SPRINGFIELD, OHIO, ASSIGNOR TO THE CHAMPION CHEMICAL COMPANY, OF SPRINGFIELD, OHIO, A CORPORATION OF OHIO.

DESIGN FOR A BURIAL-VAULT.

47,382.

Specification for Design.

Patented May 25, 1915.

Application filed March 30, 1914. Serial No. 828,408. Term of patent 7 years.

To all whom it may concern:

Be it known that I, CHARLES L. JOHNSON, a citizen of the United States, residing at Springfield, in the county of Clark and State of Ohio, have invented a new, original, and ornamental Design for a Burial-Vault, of which the following is a specification, reference being had to the accompanying drawing, forming part thereof.

The figure is a perspective view of the burial vault showing my design.

I claim:

The ornamental design for a burial vault, as shown.

CHARLES L. JOHNSON.

Witnesses:

CHAS. I. WELCH,
ESTHER E. PFEIFER.
